CONDIMENT SHAKER

Robert R. Collins, Weed, Calif.

Application April 27, 1946, Serial No. 665,563

5 Claims. (Cl. 65—45)

1

This invention relates to an improved condiment shaker of the type adapted for receiving and selectively dispensing two different condiments, such as salt and pepper.

The primary object of the present invention is to provide a condiment shaker of the above kind having two compartments for the different condiments, and improved valve means for selectively dispensing the respective condiments from the respective compartments.

A more specific object of the present invention is to provide a valve means of the above kind which is efficient, simple in construction, and easy and economical to manufacture and assemble.

More specific objects and features of the invention will become apparent from the following description when considered in connection with the accompanying drawings, in which:

Figure 1 is an elevational view of a condiment shaker constructed in accordance with the present invention;

Figure 2 is an enlarged top plan view of the condiment shaker shown in Figure 1, with the spout ring removed;

Figure 3 is an enlarged fragmentary vertical section taken on line 3—3 of Figure 1;

Figure 4 is a perspective view of the leaf spring for normally positioning the valve plate;

Figure 5 is a view similar to Figure 3 taken on the plane of line 5—5 of Figure 2;

Figure 6 is a central vertical sectional view of the container forming part of the condiment shaker;

Figure 7 is an enlarged perspective view of the cap for the container;

Figure 8 is an enlarged perspective view of the valve plate;

Figure 9 is an enlarged perspective view of the removable pin or intermediate portion of one of the guide loops of the container cap.

Referring in detail to the drawings, the illustrated embodiment of the invention includes a container 5 having a neck 6 at the top and divided into two substantially similar open top compartments 7 and 8 by an imperforate vertical transverse partition 9. A cap 10 is removably secured on the neck 6 and has a sifter top 11 provided with an imperforate medial portion 12 contacting the upper edge of the partition 9 to render the compartments 7 and 8 non-communicating. Pin and bayonet slot connections 13 are preferably used to detachably secure the cap 10 on the neck 6 of the container 5.

Upstanding guide loops 14 and 15 are fixed to

2

the sifter top 11 near opposite ends of the medial portion 12, the loop 15 preferably consisting of spaced end ear members 16 and a removable intermediate member in the form of a pin 17. The pin 17 has its ends removably received in the openings of the members 16, and is provided with a reduced intermediate portion 18, for a purpose which will later appear.

A valve plate 19 is slidable on the upper surface 10 of the sifter top 11 and has pairs of slots 20 and 21, respectively, extended inwardly from its edge at diametrically opposite points. The slots 20 and 21 provide guide tongues 22 and 23 therebetween, which tongues are slidable in the respective guide loops 14 and 15. The tongue 23 extends outwardly of the cap and has its outer end directed downwardly to form a finger piece 24. An upstanding retaining loop 25 is fixed to the valve plate 19 at the inner end of the tongue 20 23 and inwardly of the guide loop 15.

A leaf spring 26 has its ends engaged under the loops 14, 15 and 25, and is formed to exert a downward pressure on the valve plate 19 between the guide loops 14 and 15, as well as a lateral pressure against the retaining loop 25 of valve plate 19 to normally position the latter with the retaining loop 25 disposed against the inner side of the guide loop 15. This limits movement of valve plate 19 in one direction under the influence 20 of spring 26, at which time the finger piece 24 is in projected position. The spring 26 has spaced upstanding spring loops 27 which respectively bear against the inner side of the guide loop 14 and the inner side of the retaining loop 25 of the valve plate 19. Spring 26 further has a downwardly arched portion 28 between the spring loops 27 which bears on the valve plate 19 and holds the latter in intimate contact with the upper surface of the sifter top 11 of cap 10. It will be noted that an end of spring 26 engages in the reduced intermediate portion of pin 18 between the larger ends of the latter so as to retain said pin in position with respect to the ear members 16 of the guide loop 15. The purpose of providing the removable member or pin 17 is to allow for assembly of the parts, the tongue 22 being engaged under loop 14, and pin 17 being inserted after the tongue 23 has been lowered into position between the ear members 16.

50 The sifter top 11 has perforations 29 and 30, respectively at opposite sides of its medial portion 12. Valve plate 19 has similar perforations 31 and 32 at opposite sides of its medial portion 33, the perforations 31 coacting with the perforations 29 and the perforations 32 coacting with the per-

forations 30. The arrangement is such that, when the valve plate 19 is in its normal position, perforations 32 are aligned with perforations 30 so that the condiment may be dispensed from the compartment 7, the perforations 31 being at this time out of registry with perforations 29 so as to prevent dispensing of the condiment from the compartment 8. Also, when the valve plate 19 is moved by pressing inwardly on the finger piece 24 against the action of spring 26, the perforations 32 are moved out of registry with perforations 30 and the perforations 31 are moved in registry with the perforations 29, thereby permitting the dispensing of the condiment of the compartment 8 and preventing dispensing of the condiment from the compartment 7.

While a condiment shaker of the present kind is capable of general use, it will be found especially useful in kitchens where repeated use of both pepper and salt is required. The chef need only reach for one shaker to obtain either salt or pepper, or both, also, either condiment may be readily selected or dispensed at will, it being simply necessary to indicate or know that the device is normally conditioned to dispense a certain one of the two condiments.

From the foregoing description, it is believed that the construction, operation and advantages of the present invention will be readily understood and appreciated by those skilled in the art. Minor changes are contemplated such as fall within the scope of the invention as claimed.

What I claim is:

1. In a condiment shaker, the combination of a container having a neck at the top and divided into two substantially similar open-top compartments by an imperforate vertical transverse partition, a cap secured on said neck and having a sifter top, said sifter top having an imperforate medial portion contacting the upper edge of the partition to render the compartments non-communicating, upstanding guide loops fixed to the sifter top near opposite ends of said medial portion, a valve plate slideable on the upper surface of said sifter top and having pairs of slots extending inwardly from its edge at diametrically opposite points to provide guide tongues therebetween, said guide tongues being slideable in said guide loops, one of said tongues extending outwardly of the cap to form a finger piece, an upstanding retaining loop fixed to the valve plate

5 at the inner end of said one tongue and inwardly of one of the guide loops, and a leaf spring having its ends engaged under said loops and formed to exert a downward pressure on the valve plate between the guide loops and a lateral pressure against the retaining loop to normally position the valve plate with the retaining loop disposed against the inner side of said one guide loop and with the finger piece in projected position, the sifter top and the valve plate having coacting perforations, certain of which are registered with respect to one compartment and others of which are out of registry with respect to the other compartment when the valve plate is in normal position, said perforations being respectively arranged to be registered with respect to said other compartment and moved out of registry with respect to said one compartment when the valve plate is moved by pressing inwardly on the finger piece.

10 2. The construction defined in claim 1, wherein said leaf spring has spaced upstanding spring loops respectively bearing against the inner side of the other guide loop of the cap and the inner side of said retaining loop of the valve plate, and a downwardly arched portion between said spring loops bearing on the valve plate.

15 3. The construction defined in claim 1, wherein said one guide loop has a removable intermediate member.

20 4. The construction defined in claim 1, wherein said one guide loop has a removable intermediate member retained in place by one end of the leaf spring.

25 5. The construction defined in claim 1, wherein said one guide loop has a removable intermediate member in the form of a pin having a reduced intermediate portion, one end of the spring engaging the reduced portion of the pin to retain the same in place.

30 40 ROBERT E. COLLINS.
